APPARATUS FOR LINING CAN ENDS

Frank C. B. Page, Oyster Bay, N. Y., assignor to
E. W. Bliss Company, New York, N. Y., a cor-
poration of Delaware

Application April 8, 1933, Serial No. 665,081

6 Claims. (Cl. 113—80)

In tin cans or receptacles for certain purposes it is customary to employ a lining within the can end or head of paper or other flexible material. For such lining various flexible sheet products are used, such as oiled or paraffined or coated paper or various flexible materials in the nature of films. For convenience the term "paper" will be used to designate any such flexible sheet or film used as such lining.

10 It is desirable to form the head or can end with an incurved marginal flange or curled edge and to fit the paper lining at its margin within such curled edge, so that when the head is seamed to the body of the can the marginal portion of the paper lining will serve as a yielding packing for

15 the double seam.

The present invention provides an improved apparatus for inexpensively applying the linings to the sheet metal heads. This apparatus is of that class having means for punching the lining from a sheet or blank and applying it in correct relation to the head, which operations may be performed at one stroke. The head is held in exact position beneath a cutting die; the paper is fed over the cutting die, a blank holder descends upon it to hold it marginally in place; a cutting punch then descends and cuts out the paper blank; the blank is then carried down within the die and received temporarily in a recess beneath, and finally it is pushed down from said recess onto the head and its marginal portion is forced into the exterior flange of the head and within the curled edge thereof. On the return stroke of the punch members the head with its lining thus securely attached is fed out and its place taken by the next head to be lined.

For accomplishing these punching and uniting operations a double-action press is used having relatively movable concentric punching members. Such press may in general be of the character set forth in the patents of E. W. Bliss Company, No. 796,534, August 8, 1905, and No. 859,977, July 16, 1907; these being named merely as instances of a general type of double-action press which, with proper modification of its punching members, may be applicable for practicing the present invention.

The accompanying drawings illustrate the preferred construction of a suitable double-action press and illustrate the steps in the process and the completed product.

Fig. 1 is a vertical mid-section through the bed, die and punching members, showing the latter at the bottom of the stroke, having just finished

55 the lining operation.

Fig. 2 is a fragmentary plan partly in horizontal section taken mainly on the planes of the line 2—2 in Fig. 1.

Fig. 3 is a section similar to Fig. 1 on a smaller scale, showing the punching members at the instant of cutting the paper blank, the plane of the section being at right angles to Fig. 1, so as to show the feeding of the paper to the die.

Fig. 4 is a half-section of certain of the parts shown in Fig. 1, showing the punch members at 65 top stroke.

Fig. 5 is a fragmentary half-section similar to Fig. 4, but showing the punch members on the down stroke and while carrying the blank down within the die.

Fig. 6 is a diametrical section of the finished, lined head or can end on a larger scale.

Fig. 7 is an inverted plan of the head with its paper lining partly broken away.

Fig. 8 is a fragmentary view on the same scale 75 as Fig. 6, showing the position of the punch members at the end of their down stroke.

Referring first to Figs. 6 and 7, the head or can end A is shown as having a raised middle portion a surrounded by an annular raised portion b exterior to which is a flange c having an incurved marginal portion or edge d. For a can top, the position shown in Fig. 6 is inverted, the raised portion a in this case being a depressed portion. For a can bottom, the arrangement shown in 85 Fig. 6 is that which the parts would occupy in the finished can. For a can top having a friction lid or cap, the latter (lettered B) is formed with a tapered portion wedged within a tapered neck e formed in the annular head A. This is the 90 usual construction of friction top can heads. That side of the head which is to face the interior of the finished can is covered with the liner or lining C, the middle portion of which rests against and is supported by the raised portion a of the 95 head, and the outer portions of which are pressed into approximate conformity with the outer annular portions of the head, its marginal portion being entered down within the flange c and its edge curled inside the curled edge d of the metal head. This is the usual way of applying such liners. When the head is seamed to the end of the can body the paper within the curled edge d and flange c serves as a packing between the double flanged portions of the can body and head. 100

The machine will now be described. D is the usual fixed bed of a double-action press. E is the usual head slide thereof, and F the usual punch slide. Just over the bed D turns an intermittently rotating dial or turntable G. This is 110

- shown as in annular form, being a ring dial turning around a fixed central boss or hub G'. It is rotated intermittently by usual mechanism (not shown). It is formed with a series of openings 5 or recesses 12, 12 to receive the heads A. In Fig. 2, two of these heads are shown in place in these recesses, to which they have been fed by hand or by any suitable feeding mechanism such as is common in such machines (not shown). The 10 dial feed brings the openings 12 of the dial G successively into position, accurately centered beneath the punch members. Figs. 3 and 4 show the head to be lined thus positioned.
- On top of the bed D and suitably fastened thereon above the top of the dial G is the cutting die H, its inner margin being of the contour of the paper blank to be cut. It is shown as supported within a bolster I fastened down to the bed by bolts 14. The opening in the cutting die is slightly 15 expanded downwardly, as shown at 14', Fig. 1.
- The head slide E carries the usual blank holder 20 J and cutting punch K; the punch is tubular and conforms exteriorly to the opening in the die H; while the blank holder J encloses the cutting punch and in action comes down upon the top of the die H and forcibly holds down the paper blank 25 thereon. In the construction shown the punch K is fixedly held in a bolster L fastened beneath the slide E; while the blank holder J is relatively 30 movable, being guided by pins 15 and pressed down by springs 16. The pins 15 have heads sliding in recesses 17 in the bolster L and bottoming thereon on the upstroke so as to carry up the blank holder as shown in Fig. 4. The springs 35 16 (of which three are shown) are guided in recesses 18, press downwardly against the flanged portion of the blank holder and react upwardly against brackets 19 fastened down on top of the head plate M intervening between the slide E and the bolster L. (Or any other usual construction may 40 be substituted).
- The punch slide F carries beneath it in usual manner the punch body N which reciprocates 45 within the bolster L and cutting punch K in usual manner. To its lower end is fastened an annular punch member or presser foot P and within this (according to the shape or construction of the head A to be lined) are one or more yielding pads. In the precise construction shown there is a 50 middle pad Q movable within a yielding pad member R, the outer marginal portion of which surrounds the pad Q and occupies the annular space between this pad and the punch member P. In the construction shown the member P is rigidly 55 fastened to the punch body N; the pad member R is movable within it, being pressed down by a somewhat heavy spring 20; and the middle pad Q is movably attached within the member R and pressed down by relatively lighter springs 21.
- The middle pad Q corresponds to the raised 60 portion a of the head; and the surrounding annular portion of the pad R corresponds in location to the annular raised portion b of the head A; and the punch member P corresponds in position 65 to the annular flange c of the head. The contour of the member P is such that at the bottom of its stroke it fits around the annular member b of the head and conforms to its flange c entering within the curled edge d (all as shown in Fig. 8).
- In operation the paper to form the lining C is 70 fed as a strip 25 from a roll 26 by means of intermittently turning feed rolls 27 (Fig. 3). Fig. 2 shows the strip 25 guided between flanges 28, 28 of a parallel paper guide 30. During the 75 paper feeding the punch members are elevated

as in Fig. 4; in this position the pad member R is held up by a pin key 31 seated in the punch head N and engaging a notch in a central stem 32 fixed to the member R.

The slide E descends in advance of the slide F, and its blank holder J which projects slightly lower than the cutting punch K first engages the fed paper and clamps it against the cutting die with all the force of the springs 16. Instantly thereafter the further movement causes the punch K to cut through the paper and carry it downward into a recess which is shown as within the die H, and in which recess it is temporarily held in the position shown in Fig. 5. From this point in the stroke the slides E, F move nearly together so that the punch members K, P, R and Q descend at substantially the same speed within the die H; they are shown about half way through this die in Fig. 5. The cutting die K is stopped in the position shown in Fig. 1, at the limit of down stroke of the slide E; thereafter the movement of the slide F continues and carries down the inner members P, R, Q to the bottom of their respective strokes. Moving down together they carry the paper blank 100 to the position shown in dotted lines at x in Fig. 4, where it strikes the top of the middle raised portion a of the head A; at this point in the stroke it is clamped against a by the pad Q, with the pressure imparted by the springs 21. Following 105 immediately behind the pad Q comes the pad member R which continues its descent until it is stopped by contact with the annular portion b of the head, thereby slightly crimping the paper and clamping it annularly against this part of 110 the head. This leaves the annular marginal portion of the paper blank projecting circumferentially around this clamped portion. Instantly thereafter the continued descent of the punch member P brings it into contact with this marginal portion of the paper and it carries the latter down, conforming it to the tapered exterior of the portion b and forcing it down into the flange c of the head. In this downward movement the outer edge of the paper is directed inwardly by a coned portion 12' of the opening 12, as shown in Figs 3, 4 and 5. It will be observed 115 that the paper lining is cut to a larger circle than the outer contour of the head so as to provide sufficient material for the downwardly conformed portion of the lining. Thus during this portion of the stroke the outer edge of the paper keeps traveling inward, and at the end of the stroke of P it is carried down against the bottom flange c and its outer edge is tucked within 120 the curled edge d of the head as shown in Fig. 8. Thereupon the ascending stroke of the punch occurs, lifting its members Q, R, P free from the head; as these members pass up the slide E rises with a slightly delayed movement, lifting the 125 cutting punch K out of the die H and finally lifting the blank-holder J off from the die, whereby the parts are restored to their initial position shown in Fig. 4. Thereupon the dial G turns one movement, carrying the lined head beyond to 130 the position shown at 12a in Fig. 2 and bringing the next head into place beneath the punch members. Simultaneously the next feed of the paper strip 25 takes place. The operation is 135 then repeated.

The machine thus described performs in one 140 operation the two operations of (1) cutting out the paper blanks, and (2) uniting the paper blanks to the heads. It thus avoids the necessity of successively feeding individual paper blanks, 145 150

with the disadvantage of occasionally feeding two blanks together, which results in applying a double thickness of liner to the head. The operation is as rapid as the speed at which the press can be driven. The coincident location of the cutting dies and uniting means for performing both operations at one stroke is not new per se and is not essential to my invention.

While the construction shown and described is preferred, it will be understood that this may be varied according to the particular construction and shape of the head to be lined and the particular material (paper or other sheet or film substance) which may be required for the lining. Accordingly the punch members P, Q, R may be varied in proportions, number and arrangement, and in the downward pressure applied to the movable member or members, as may be requisite to adapt the mechanism to any required conditions.

I claim as my invention:

1. Apparatus for uniting a paper lining to a flanged metal head having a curled marginal edge, comprising a cutting die and punch, means for holding the head in place beneath such die, and punch members movable down within the cutting punch and die comprising a spring-pressed pad adapted to clamp the lining against the head, and a separately-movable annular punch portion movable down subsequently into the flange of the head and adapted to force the edge of the lining within the curled edge of the head.

2. Apparatus for uniting a paper lining to a flanged metal head, comprising a cutting die and punch, means for feeding the head and holding it in place, and punch members distinct from the cutting punch comprising a spring-pressed pad adapted to clamp the lining against the head, and a separately-movable annular punch portion movable down subsequently into the flange of the head and adapted to force the edge of the lining within the curled edge of the head.

3. Apparatus for uniting a paper lining to a flanged metal head, comprising a cutting die and

punch, means for holding the head in place, and punch members distinct from the cutting punch, and relatively movable with respect to each other, comprising an outer annular punch portion, and a spring pressed pad within it adapted to clamp the lining against the head, such annular punch portion being movable down into the flange of the head after the spring pressed pad has been arrested and being adapted to force the edge of the lining within the curled edge of the head.

4. Apparatus for uniting a paper lining to a flanged metal head having an outer flange with a curled marginal edge, an inner raised portion, and an intervening annular portion, comprising a cutting die and punch, means for holding the head in place, and punch members distinct from the cutting punch, comprising a middle pad adapted to clamp the lining against the raised middle portion of the head, a separately-movable annular pad portion surrounding it, adapted to press the lining against the intervening annular portion of the head, and an outer annular punch portion movable down subsequently into the flange of the head and adapted to force the edge of the lining within the curled edge of the head.

5. Apparatus for uniting the paper lining to a flanged metal head having a curled marginal edge, comprising a cutting die and punch adapted to cut out the paper lining, the die having a recess therein for temporarily receiving the cut lining, means for holding the head in place, and uniting means coincident with the head and movable to carry the lining from said recess against the head, comprising a pad for pressing the lining against the top of the head, and a separately-movable annular punch portion, with means for moving it subsequently downward to force the edge of the lining against the flange of the head and within its curled edge.

6. Apparatus according to claim 5, with an annular holder for the material from which the lining is to be cut surrounding the cutting punch and movable in advance of such punch to clamp the material against the top of the cutting die.
